UNITED STATES PATENT OFFICE

2,204,417

AUTOMATIC WRAP STRIPE KNITTING
MACHINERobert H. Lawson, Pawtucket, R. I., assignor to
Hemphill Company, Central Falls, R. I., a corporation of Massachusetts

Application October 13, 1937, Serial No. 168,766

23 Claims. (Cl. 66—25)

This invention concerns a knitting machine for incorporating in a knitted fabric certain pattern threads by means of so-called needle wrapping, the invention being more especially concerned with applying such wrapping thread incorporating means in a machine adapted to knit a complete stocking. That is, wrapping the pattern threads is to be combined with the knitting of all the essential features of the ordinary stocking or half hose including the knitting of a rib top, transfer to knitting at the termination of the top and thereafter knitting a plain leg, foot including the heel and toe, as well as other essential elements.

15 In the figures of drawings:

Fig. 1 is a section showing more or less of the complete assembly wherein the novel wrapping means is included in the combination with a dial and cylinder knitting machine adapted to transfer stitches from the dial to some of the cylinder needles;

Fig. 2 is an elevation showing part of the machine of Fig. 1, especially the controlling connections for operating upon certain elements for imparting wrapping movements to the wrap thread guiding elements and other control for some of the dial and transfer cams;

Fig. 3 is a section showing part of what has been illustrated in Fig. 1, but to a scale much larger than that employed in that figure;

Fig. 4 is a transverse section through a portion of the machine illustrating the drive for the wrapping head assembly and the means through which the individual wrap thread guiding elements are being caused to wrap the threads about needles;

Fig. 5 is a plan of the top of the machine wherein certain parts are shown, which parts have the function of controlling the dial for transfer;

Fig. 6 is a section taken through the elements shown in Fig. 5 and illustrating to greater detail the manner of driving the dial;

Fig. 7 is a plan of certain parts at the top of the machine and showing connecting elements for the control of the dial and transfer cams;

Fig. 8 is a transverse section taken through Fig. 7;

Fig. 9 is a section showing in detail one of these cam controlling connections;

Fig. 10 and 11 are similar views showing details of other connecting elements which are active during cam changes as for knitting and transferring;

Fig. 12 is a section showing a fragment of the

wrapping mechanism, especially the sector for reversely rotating the wrap thread guiding spindles;

Fig. 13 is a sectional view on line 13—13, taken through the sector and one of the spindles and gears shown in Fig. 12;

Fig. 14 is a section taken through Fig. 12 as viewed from the outside of the machine;

Fig. 15 is a view similar to Fig. 12, but showing a fragment of the wrapping mechanism at 10 the opposite side of the machine, especially the sector which is active to rotate the wrap thread guiding spindles when they wrap their needles;

Fig. 16 is an elevation showing the parts shown in Fig. 15 as seen from the outside of the 15 machine;

Fig. 17 is a sectional view showing the entire assembly of wrapping spindles and the means for maintaining them in position as they are controlled by the sectors, above mentioned;

Fig. 18 is a section on line 18—18 of Fig. 17 showing in detail the wrap thread guiding spindle retaining means;

Fig. 19 is a diagrammatic view illustrating the movements of the wrap thread guiding fingers 25 as they pass through their thread wrapping cycle;

Fig. 20 is a section showing the cam means employed for ratcheting the pattern drums which are to control the selection of needles to 30 be wrapped;

Figs. 21—24 show different positions of a wrap-
ping spindle as affected by the wrapping sector;

Figs. 25—32 show progressive positions of the wrap thread guiding fingers as they move 35 throughout their thread wrapping cycle;

Fig. 33 is an elevation taken at the front of the machine showing the cylinder, various cams and picks employed, and the general arrangement of the selecting means for selecting needles 40 to be wrapped;

Fig. 34 is a transverse section taken through the cylinder and illustrating the various cams and picks which function upon needles and jacks associated with needles other than selecting 45 jacks;

Fig. 35 is a transverse section taken through the cylinder below the cam plate of Fig. 34 and showing the general arrangement of selecting means for functioning upon needle selecting 50 jacks;

Fig. 36 is a section similar to that of Fig. 35 but illustrating in detail certain selecting means for making a plain sole etc.;

Fig. 37 is a plan view showing the latch opener; 55

Fig. 38 is an elevation showing parts of the mechanism for controlling the yarn feeding fingers, certain parts being shown in section;

Fig. 39 is a plan view showing the sinker cap, associated parts, and the control for sinker cams;

Fig. 40 is a section on line 40—40, Fig. 39, showing details of a special sinker cam;

Fig. 41 is a section on line 41—41, Fig. 39, showing the latch opener and adjacent portion of 10 the sinker cap;

Figs. 42 and 43 are sections showing details of the sinker cams;

Figs. 44—51 are diagrammatic views which illustrate the function of the various cams and 15 selecting means for controlling needles and jacks throughout the different phases of knitting;

Figs. 52—57 are sectional views showing the 20 needles and associated jacks, the selecting jacks in various positions of operation, and also the 20 different types of jack employed; and

Fig. 58 is an isometric view showing one particular set up of needles and selecting jacks for making certain patterns.

Automatic half-hose machines have been 25 known for some time, but have been limited to the knitting of hosiery of a plain type, that is, without ornamentation, or with simple types of ornamentation such as plating and reverse plating, horizontal striping and somewhat limited designs by a simple method of needle wrapping. The automatic half-hose machine herein illustrated is adapted to knit a true rib top on conventional dial and cylinder needles of the latch type, and in addition, to knit the remaining parts of 30 the stocking after a transfer from dial needles to cylinder needles which were inactive during the knitting of the rib top. The rib top and the remaining parts of the stocking are preferably knitted with the same number of wales throughout. Reference is hereby made to copending application Ser. No. 86,814 for a full disclosure of a machine very similar to the machine herein illustrated, but without provision for knitting a pattern of any sort. To that basic type of machine has been added needle wrapping mechanism adapted to wrap needles for the knitting of fabric ornamented with what is generally known as a true wrap pattern. This wrap pattern may involve a great number of colors, may 45 be knitted on any selected needles throughout the entire group of cylinder needles and has a sufficient scope to produce "color side of color" and "color within color" patterns.

The knitting of a half hose has been accomplished entirely on one machine and as described in application Ser. No. 86,814 involves a machine having twice as many cylinder needles as dial needles, the usual sinkers operable with the cylinder needles for knitting plain fabric and the necessary cams for functioning upon all cylinder needles during plain work or knitting in the heel or toe as well as cams for controlling a part only of the cylinder needles during the knitting of the rib top. The dial has associated therewith the necessary cams for the control of dial needles while knitting rib fabric, also the necessary transfer cams to control dial needles for projecting them outwardly and withdrawing them into the dial at transfer. It is also essential to provide transfer cams which come into play at the necessary time for the control of the cylinder needles so as to actuate needles to penetrate and receive certain stitches from the dial needles at the termination of knitting the rib top and prior

to starting out in the plain knitting incidental to the leg of the stocking.

It has been found convenient and of advantage to employ an unusual system of knitting as far as the cylinder needles are concerned, this system not being broadly new in this particular case, but forming the subject matter of copending applications Ser. Nos. 695,154, now Patent #2,127,178 and 144,007, now Patent #2,158,189 wherein the same has been described in considerable detail. This system of knitting involves the use of a combined needle and jack which function together at certain desired parts of the knitting cycle, but which are separable and function in a separated relationship during other 15 phases. Both the needle and jack are provided with a butt, the jacks having all butts alike while the needles are provided with butts of different lengths. At times one or both instruments are caused to function by the engagement of cams with the needle butts and at other times, the engagement of the particular actuating cams involved is with jack butts. At certain phases of the knitting the jacks are disconnected from needles as described in the applications above indicated and are ineffective to impart any movements to the needles, and at such times, these needles will remain inactive or merely be controlled by such cams as engage their own butts. This system of knitting makes it possible to perform many parts of the knitting with the needles in a low position, and thus to have more room above the sinker head or stitch ring and to provide more space for the dial and wrapping mechanism which must function in close proximity to the top of the dial and just above the sinker head, stitch ring, etc. The latch ring as commonly known is not to be employed with this type of machine since in the low position in which needles pass about the machine, their latches 40 will be maintained in open position by engagement of stitches hanging on the latches prior to being cleared. Of course, it is necessary to provide something in the nature of a mouthpiece which will control needle latches at the knitting point and through which the usual knitting yarns 45 may be fed.

In addition to the mechanism necessary for wrapping the various wrap threads about selected needles, jacks are to be employed under the 50 needles which will impart predetermined selecting movements thereto in accordance with some conventional selecting means such as a trick-wheel, jacquard strips, or the like. Since the machine is constructed for the knitting of "color 55 side of color" and "color within color" patterns, two selecting stations are employed, it being possible to select any of the jacks and thus any of the needles at either station, and to wrap them with one thread at one station or with another 60 thread at the other station all as will be described as the description progresses.

GENERAL DESCRIPTION

Now referring to Figs. 1, 2, 3, 5, 6, 7—11 and 65 52—57, I will describe the general characteristics and arrangement of the knitting machine to which thread wrapping mechanism has been applied. In Fig. 1 the base of the machine is shown at 1, a needle cylinder at 2, ring gear for driving that needle cylinder at 3, a sinker head 4 and a cap 5, these parts all being of a more or less conventional construction as considered in a general way. The mechanism described involves a rotatable needle cylinder such as employed in 75

Banner machines but it is equally possible to apply the principles of this invention to rotating cam and stationary cylinder machines; the reversals necessary will be evident to those skilled in the art if it is desired to apply such principles to that type of machine. A series of upright posts 6, preferably three in number, project upwardly, two of them from the so-called circular base of the machine, and support fixed horizontal plates 7 and 8 as well as guiding a movable horizontal plate 9.

The uppermost plate 8 is formed into a somewhat elongated hub 10 within which is clamped a long tube 11 which extends down to almost the upper end of the cylinder and within which is rotatably held a spindle or shaft 12 to the lower end of which is attached the dial 13. This dial has a hub 14 which is pinned to the lower end of shaft 12 by means of a taper pin 15. The dial is slotted in the usual way and dial needles of more or less conventional type are slidable within said slots. These dial needles will have butts of two different lengths, this difference in length being mainly for the purpose of bringing cams into position on the short butts whereupon they will engage the long butts and move to a fully operative position. The dial cap generally indicated by elements 16 and 17 rests upon the dial itself and is held against rotation since the dial cams 18 and 19, movable up and down within openings in the top of the dial cap, are restrained from turning by means of their engagement within sleeve 20 and upon bushing 21. The sleeve 20 has slots 22 and 23 within which the outer ends of pins 24 and 25 are guided, these pins being threaded into cams 19 and 18 respectively. The slots 22 and 23 limit the extremities of movement for the said cams; of course, these cams engage the butts on dial needles in lower position and are disengaged therefrom when in upper position. The cam 18 is employed as a transfer cam while cam 19 is a knitting cam. The rods 26 and 27 extend downwardly from the top of the machine closely adjacent to the tube 11 and are slightly offset at their lower ends to engage pins 24 and 25 between the upwardly extending stems on the cams 19 and 18 and the slotted portions of sleeve 20, these rods imparting operating movements to the said cams in accordance with the control derived from cam drums on the machine and throughout the different phases of knitting.

As shown in Figs. 1, 3 and 52-57, needles 28 of a pivoted latch type have associated therewith jacks 29, both needles and jacks slideable within the usual tricks or slots cut in the cylinder. The cylinder has a slotted stitch ring 30 at its upper end, this ring guiding the inner ends of sinkers and also supporting the fabric as it slides down within the space inside the cylinder. Each of the needles has a butt 31 although these butts are of different length on different needles spaced about the cylinder. The arrangement of these different length butts and their purpose will be described in due course. Each of the jacks has a butt 32, this butt 32 being of the same size on all jacks. The lower end 33 of each jack fits within a notch formed in the upper edge of the needle butt, and adjacent the other end of the jack a beveled projection 34 engages within a corresponding indentation 35 in the needle. The beveled upper edge of this projection is of such an angle that movement imparted to the jack in an upward direction will cause a corresponding movement of the needle. Of course, down-

ward movements of the jack will move the needle downwardly throughout a similar extent. A series of springs 36 retain jacks and needles within the slots in the cylinder. However, at certain desired times the needle will be held in one position by engagement of cams with butt 31, and by means of other cams or picks, the jacks will be separated from the needle. This separating movement is easily provided by the bevel on the projection 34, and a smooth engaging and disengaging action is obtained even though under normal circumstances these engaging parts provide a means for transferring motion from one element to the other.

Each of the needles has a selecting jack 37 positioned in the slot beneath it and these jacks have a plurality of removable selecting butts and other butts, the function of which will be described more fully in a later paragraph. These jacks are held inwardly of the cylinder within the slots by means of a plurality of springs 38. The various cams and selecting elements which function upon these jacks will also be described when that portion of the mechanism is discussed in detail.

Now referring to Figs. 1, 3, 5 and 6, the base of the machine 1 is extended at 39 and a casing or cap 40 bolted to the top of the extension has an opening or provides an annular space within which a gear 41 is enclosed. This gear meshing with a second gear 42 bolted to the ring gear 3. The number of teeth on gears 40 and 42 is the same so that a shaft 43 running within a hub 44 fixed to the cap 40 is driven at the same speed as the needle cylinder. This gear 41 is fixed by means of a taper pin 45 or by any other suitable connection to the shaft 43 so as to drive and also retain that shaft in proper axial position. A second shaft 46 is attached by means of coupling 47 to a fixed end and extends upwardly through suitable bearing elements in each of the horizontal plates 7, 8 and 9. The plate 7 has a hub or bearing element 48 attached to the underside thereof within which said shaft 46 is guided, and plate 8 has a similar hub 49 for the same purpose. A collar 50 is adjustably attached to the said shaft and positions the same axially resisting thrust of the shaft in an upward direction.

The shaft passes upwardly through an opening in plate 8 and has attached a gear 51 which is similar to the gear 41 having the same number of teeth. That gear 51 meshes with a second similar gear 52 which has an enlarged hub 53 that turns upon the hub portion 10 which is more or less central of the plate 8. This gear 52 will eventually be driven at the same speed as the needle cylinder. Plates 54 and 55 are attached to the upper side of the plate 8 and enclose the teeth of the gears 51 and 52; they also retain those gears downwardly within the counter-bored openings within which they rotate. Now referring to Figs. 5 and 6, a more detailed illustration of this mechanism at the top of shaft 12 is shown and will be described. That shaft 12 has a brake drum 56 attached at the extreme upper end, this drum being restrained from turning on the shaft by means of a key 57. The position of the shaft within the hub of the drum and, incidentally, the vertical height of this shaft and of the entire dial assembly, is controlled by an adjustment of the nut 58 which is held in an adjusted position by a lock nut 59. The tube 11 has a long keyway 60 cut in its upper end within which fits a key 61. This key 61

is a part of a collar or washer 62 which is fixed to the hub 10. The tube 11 is thus prevented from rotating but is free to be moved vertically within the hub 10 and washer 62. This vertical movement allows the entire dial assembly to be moved upwardly for gaining access to the parts within the cylinder or at the upper end thereof and for any other desired purposes. The cap of the brake drum 56 has an opening therein at 63 and a downwardly projecting lug 64 extends through this opening, this lug having annular projecting parts as at 65 at the upper end by means of which it is attached to the drum by suitable screws 66 or other connections. This lug 64 passes downwardly between two projecting arms 67 extending outwardly from the hub of the gear 52. Each of the arms carries an adjustable screw 68 and lock nut 69. These adjustable screws 68 are set at a proper position to drive the dial by means of the gears 42, 41, shaft 46, gears 51, 52, lug 64 and brake drum 56 as it rotates shaft 12. These screws 68 provide for the proper spacing of dial and cylinder needles during the knitting of rib work, and whenever a brake 70 at one end of a lever 71, pivoted within a bracket 72, is applied to the brake drum 56 and a latch 73 shown in dotted lines, Fig. 5, pivoted on the post 74 is removed from engagement with lug 64, the dial will be shogged relatively to the cylinder and will be driven through contact with the screw 68 rather than through the latch 73. All this takes place during transfer and is clearly shown and described in detail in application Ser. No. 86,814 so will not be described in greater detail in this case. Of course, during the knitting of plain work, the dial is rotated idly by means of the mechanism just described. It will be rotated in its retarded or shogged position until the first stroke in the heel whereupon the reverse rotation will bring about an engagement of the latch 73 with the lug 64. Of course the brake 70 was disengaged after transfer was complete. A further adjustment for the position of the tube 11 as well as for the dial assembly is provided in the elongated screw 75 threaded down through the web of brake drum 56 and bearing upon the hub of the gear 52. A lock nut 76 maintains this adjustment.

Now referring to Figs. 1, 2, 3 and 7-11, the control for the various dial cams will be described. The rods 26 and 27, rectangular in cross-section, extend upwardly, close to the tube 11, and adjacent their upper ends connect to similar extending rods or bars 77 and 78. Each of these bars has an elongated slot cut therein which engages about a shoulder screw 79 threaded into the upper end of each of the rods first mentioned. When the dial assembly is moved upwardly these slots provide for the necessary upward movement of the rods 26 and 27.

The lower part of the hub 10 is flattened at either side as illustrated in Fig. 7, and this flattened side is milled out as shown in Figs. 6 and 7 to receive the upper ends of the bars 77 and 78. Plates 80 are bolted to these flattened sides and are also slotted horizontally, that is, perpendicular to the slots in the hub itself. Each of these plates 80 is extended to the front of the machine as at 81, and this extending part has a shoudered screw 82 threaded therein for engagement with a slot 83 in the horizontally disposed bar 84 which functions to control the transfer cams while a similar construction is evident at the opposite side with bar 85 which controls the rod

77 and incidentally the dial knitting cams. These bars 84 and 85 slide within the horizontal grooves within the caps 80 and are also guided by the screws 82 mentioned. Each of the bars has a cam slot 86 within which a pin 87 slides, one of these pins 87 being threaded into the upper end of each of bars 77 and 78. The pins stick outwardly through a slotted opening in the caps. Evidently horizontal movements of the bars 84 and 85 will cause vertical movements of the bars 10 77 and 78 respectively, such movements being imparted to the respective sets of cams for the control of dial needles. At a pivot 88, Figs. 2, 7 and 8, and at another pivot at the opposite side at 89, both of these pivots projecting from bracket 90, are attached bell crank levers 91 and 92. The bell crank lever 91 engages a roller or follower 93 at the end of bar 84 and will pull that bar outwardly to the position shown in Fig. 8 when thus moved by means of a downwardly extending rod 94. This rod 94 is controlled from suitable connections to a pattern drum not shown in this case, but clearly shown and described in copending application 86,814. Return movements of the bar 84 are controlled by spring 95 attached to the bar and to the extension 81. The bell crank 92 likewise engages a roller 96 at the end of bar 85 and control is from the same cam drum or a similar cam drum through the rod 97. A spring 98 similar to that on the other side causes the return movements and these return movements serve to push the bars 77 and 78 downwardly. It is obvious that the bars 77 and 78 may raise the rods 26 and 27, but due to the particular construction, cannot push them down. Springs 99, one of which is attached to each of these rods and to a fixed part of the machine, serve to move the rods 26 and 27 and the cam assemblies at either side of the dial down, these springs further serving to allow the said cams to rest on short butts and thereafter drawing or forcing them down to engage both long and short butts. So much of this part of the description has been given herein to impart a general knowledge of the construction of the machine itself and it is not felt that further description is necessary in view of the fact that up to this point, all essential features have been described and claimed in the prior applications to which attention has been called.

NEEDLE WRAPPING MECHANISM

Now referring to Figs. 1, 3, 4 and 13-32, I will describe the devices which operate to wrap pattern threads about such needles as are selectively raised to receive them. The plate 9 is supported on the uprights 6, the hub 100 having a sliding fit with one upright member, and further being slidable along the shaft 46 by means of the special construction of hub 11 and attendant parts. The engagement with these latter elements is, of course, a sliding one. The plate 9 has a large annular opening within which fits a flanged ring 101; this flanged ring 101 is also attached to a ring gear 102 which is driven by another gear 103 keyed to the shaft 46. Each of these gears is similar in size so that the gear 102 is driven at the same speed as the needle cylinder. The plate 9 has a hub 104 attached thereto by means of certain connecting screws 105 passing through enlarged openings in a projection 106 on the hub and being threaded through an extension or part 107 of the plate. These enlarged openings provide a certain amount of adjustment so that the centers of the bearings within which the gear 103 rotates

will be spaced properly with respect to the hub which fits about tube 11. This hub 104 attached as an extending part of the plate 9 provides a bearing for a downwardly extending part 108 from 5 the said gear 103. This gear is to rotate as driven by shaft 46 and keys 109, one at either side of the shaft, pinned into keyways cut in the hub or extension 108 of the gear. These keys also engage keyways 110 cut in the shaft to impart the 10 necessary driving movements but to allow vertical movement of the gear along the shaft as it is necessarily moved up or down when the entire wrap assembly is lifted out of position and returned thereto. A collar 111 has set screws 112 15 which fix it at any desired position along the shafts and thus determine an adjustable low limit for the entire wrapping assembly. It is not essential to support this plate 9 and all attached mechanism at the opposite side when it engages 20 the post 6, although, if desired, a similar, adjustable support of some sort might be used at that position.

The gear 102 is formed with a large opening at the center which has a bearing on a shouldered 25 part of a hub or sleeve 113, the gear being free to turn on that bearing. The said hub 113 is formed with an inner diameter which gives a tight fit on the tube 11, this inner part being cut out at opposite sides as shown at 114, Figs. 1, 3, 4 30 and 17 so as to allow free movement of the rods 26 and 27. As shown in Fig. 17, this hub is held on the tube 11 by means of set screws 115, or by other suitable means. When the tube is raised as previously described, this entire assembly on plate 9, etc. will be lifted and thus the wrapping mechanism as well as the dial will be removed from the vicinity of the tops of needles. When in raised position a hook 116 attached to an 35 angular piece 117 is to engage a projection 118, a part of another angular bracket 119 which is connected to the underside of the plate 7. This hook will maintain these assemblies in raised position until it is desired to lower them whereupon it will be unlatched and the knitter will 40 hold the dial and wrapping head mechanism while it is carefully lowered to position.

Of course, the hub 100 slides vertically upon the post 6 and the gear 103 will slide upwardly 45 on the shaft 46, but will always be rotated thereby as the keys 109 never are out of engagement with their keyways. The tube 11 is likewise held from rotating by the key 61 adjacent the top thereof although that tube is perfectly free to slide vertically within its support. When tube 11 is lifted, 50 the rods 26 and 27 are raised upwardly at the same time but their extensions, 77 and 78, are not raised as the motion is taken up by the slots 55 therein.

The gear 102 driven by intermeshing gear 103, 60 shaft 46 and gears 41 and 42 will rotate at an even speed with the needle cylinder; this gear serves to carry the individual wrapping devices presently to be described and to rotate them with the needle cylinder so that they are always in a predetermined position with respect to the group 65 of needles which each device is adapted to wrap. In this particular example I am showing twenty different wrapping devices, each of which carries two separate wrapping fingers, either of these 70 fingers being adapted to wrap a yarn about any selected needle within a group covered by the particular pair of fingers concerned. The needle or needles will be wrapped by one or the other of the fingers depending upon whether they are

raised at one wrapping point or at another. Each of the individual wrapping devices 75 comprises a short spindle 120 rotatable in a bearing in the gear 102. This short spindle has gear teeth 121 cut at the upper end thereof, there being six teeth on each of these small gears. Some of the gears have teeth of double length as shown in Fig. 14 while others have teeth of a length as shown at the left in that figure or in Fig. 13, these latter mentioned gears having an 10 extension 122 at the top so that all reach an upper position in the same horizontal plane. A plate 123 is fixedly attached to the top of the hub 113 and bears on the upper ends of the gears to hold them and their integral spindles down within 15 the bearings or openings within which they rotate in the gear 102. Each of the spindles is hollow having an opening 124 for the threads to be guided down through as they pass from the supplies to the wrapping fingers and thence to the 20 needles. The gears with long teeth correspond to the part of needle cylinder on which the instep of the stocking is to be knitted while the gears having short teeth are associated with the rest of that circle of needles and wrap the back half 25 of the stocking associated with the heel and toe, etc. The purpose of this will be described more fully when describing the wrapping of a stocking instep without wrapping the sole or high splice.

Each of the spindles has a collar 125 shrunk 30 on and each collar has two indentations 126 spaced at opposite sides thereof. A ring 127 is attached by means of screws 128 to the top of gear 102 and has a number of tappets 129 therein, one for each of the spindles and collars. 35 These tappets have a round inner end 130 and a head 131 at the other end which is grooved. These tappets are free to move inwardly and outwardly of the ring but are urged inwardly by means of a coil spring 132. This construction 40 provides for holding each of the springs in a definite position and prevents any overrunning or accidental displacement such as might take place if the spindles were loosely driven since they are only moved during wrapping and again 45 at the opposite side of the needle circle when returning to initial position.

Each spindle has a lower projection 133 of smaller diameter, the opposite sides of which are faced off to be engaged by the forked ends 134 50 of a swinging finger supporting element 135. A pin 136 passes through the forked ends and through the part encompassed thereby and is held in position by means of a set screw 137. The fingers 138 and 139 fixed in the lower end 55 of this swinging element 135 are adjustably maintained in position by means of a clamp 140. The fingers have twisted lower ends with openings therein through which the wrapping threads are to be guided.

Each of the spindles and its associated wrapping fingers is rotated once during each rotation of the machine for the purpose of imparting a wrapping movement to fingers and is then rotated backwards the same amount so as not to 65 twist the wrapping threads together and to bring the mechanism to proper position for repeating the wrapping operation on the next revolution, if desired. As shown in Figs. 4, 15 and 16, a sector 141 is arranged at one side of the machine 70 in a position to impart a rotational movement to each of the wrapping devices, this position being at the particular place where needles are selected and raised to be wrapped. This sector has six teeth for meshing with the teeth of the 75

small gears on the spindles, three of these teeth being at one end of the sector and the other three teeth being spaced therefrom and at the other end of the sector. This provides a half 5 rotation for each spindle as half its teeth contact the first three teeth designated at 142, and another half rotation as the teeth at 143 are engaged. The first half rotation would be employed for moving one of the fingers, for instance the 10 finger 138 about selected needles at the first selecting point, while the second half rotation would engage the wrap thread fed by the opposite fingers 139 with such needles as were selected at a second selecting point. Of course, 15 if only one wrapping point is used all needles would be selected at that station and the effective wrapping would be done at that point although all of the teeth 142 and 143 would necessarily be contacted in making complete wrapping 20 movements of one of the fingers. In such practice one finger only would feed a thread to these needles for wrapping them. The two selecting points and the two wrapping movements are essential when knitting some more complicated 25 patterns such as involve the knitting of different colors closely adjacent or in the knitting of so-called color within color, true wrap patterns. Of course, the fingers 138 and 139 would carry wrap threads of different color or of different 30 characteristics, and the selectivity of needles must be governed in accordance with which of the colors it is desired to wrap any of the panel of needles upon which a pattern is being produced.

35 During the entire operation of the machine the spindles and wrapping fingers are continuously rotated once during each revolution of the machine although the movement is of no consequence except when needles are selected and 40 raised to a sufficient elevation to be effectively wrapped. It is evident that the rotations of these spindles and fingers would have a tendency to twist the two wrap threads guided thereby, and after a rotation or two, the said threads would 45 be entangled to such a degree as to render the mechanism useless unless some counteracting movement were possible. A second sector 144 is located at a position somewhat opposite that of the first sector and this serves to impart rotations to each of the spindles in the opposite direction to those imparted by the sector first described. The sector 141 is external to the gear teeth 121 while sector 144 is internal or on the 50 opposite side thereof and since this last mentioned sector has six teeth it will merely return each of the spindles to its initial position after it has been rotated at the wrapping side of the machine. The plungers 129 will maintain the spindle assemblies in position between the sectors 55 so that the teeth 121 will engage the teeth on the sectors without interference, also one of the indentations 126 cooperates with a plunger to hold each spindle at a half-way position between the groups of teeth 142 and 143.

60 Each of these sectors is capable of being moved upwardly for the purpose of engaging only the teeth on those gears which have full length teeth, that is, to become disengaged from the teeth on the short toothed gears. The sector 141 has a 65 connecting bracket 145 to which is pivoted a link 146 engaging about a shoulder screw 147 threaded into the bracket. The sector itself is vertically slidable on two elongated screws 148 and 149 which extend upwardly from the plate 9. The sector has tubular elements 150 and 151

passing through openings therein and which are spaced the correct distance to engage the screws 148 and 149 so that the sector may slide vertically upon these screws without binding. The assembly is held downwardly in a position to engage all gear teeth by means of springs 152, one of these springs engaging about the upper end of the tubular sliding members 150 and 151 and beneath a washer under the head of each of the screws. The link 146 is pivoted to the outer end 10 of a lever 153 which is in turn pivotable about a shoulder screw 154 threaded into an extending bracket 155 which is connected to an angular piece 156 secured at the upper end of a rectangular post 157. A depending link 158 is pivoted intermediate the ends of this lever 153 and is in turn connected at its lower end to certain elements which impart to it movements in accordance with cams on a pattern drum. These cams will be so arranged as to move the link 158 upwardly to swing the lever and move the link 146 so as to draw the sector to an upper position against the tension of springs 152. In this upper position the sector teeth will engage only the upper half of the long toothed gears so that only 25 those spindles having gears with long teeth will be rotated; in this event, only that part of the fabric being knitted on the side having spindles with gears of the sort described will be ornamented. This provides for the making of a plain 30 sole, etc.

The sector 144, Figs. 4, 12, 13 and 14, has similar tubular guides 159 which allow it to slide up and down on the screws 160. Springs 161 maintain it in downward position while it is raised 35 by means of a link 162 pivoted at its lower end to an angular connecting element 163 secured to the sector itself. This link 162 extends up the side of the tube 11 and has a second part or extension 164, Figs. 7, 9 and 10, which is actuated 40 by means of a lever 165. The upper end of the extension 164 is guided within a slot in the hub 10 and is held therein by means of a plate or cap 166 fixed over the slot. This plate has a slot 167 through which projects a pin 168 threaded 45 into the upper end of the extension. The pin extends outwardly and is engaged by the forked end of lever 165. This lever 165 is pivoted intermediate its ends to a bracket 169 which is attached to the underside of the plate 8. A link 50 170 is pivoted to the outer end of this lever and extends downwardly to certain actuating mechanism (not shown) which is to control the movement of this mechanism in a manner understood by those familiar with this art. The controlling 55 drum which functions upon the links 170 and 158 may have cams thereon timed to raise and lower the sectors 141 and 144 whenever it is desired to knit a plain sole or other plain portion of a stocking and at the same time, to continue 60 wrapping on the remaining part of the same. The timing will be such that all of the short toothed gears which have been rotated for wrapping by sector 141 will be rotated back to initial position by sector 144 before it is withdrawn from 65 action. Of course, the sectors are never disengaged from the long toothed gears and there is no possibility of their getting out of timed relationship, which possibly might exist with respect to gears having shorter teeth if a change were 70 made within them.

The link 162 and its extension 164 have a telescoping engagement or provision for sliding relatively when the wrapping mechanism is moved upwardly as described above. This tele- 75

scoping engagement is not shown herein since it is similar to that illustrated with respect to the rods 26 and 27, Figs. 1, 8 and 11.

In addition to the plate 123 which is fixed to the upper end of the hub 113, the upper part of this wrapping mechanism is encased by a cap 171 and by a secondary covering element 172 which fits over the gear 103. This cover 172 is held upon four arms 173 attached to the hub 104. This construction forms more or less of a casing about the elements and protects them from dust and dirt as well as preventing lubricant from flying outwardly, etc. There is an annular space left between the casing 171 and the disc or plate 123 which is radially at a position just above the openings in the spindles 120. This allows the wrap threads to pass down into the openings in those spindles and also to move about the machine without interference.

The fingers 138 and 139 before described as fixed in a pivoting element 135, are more or less centrally located over the particular group of needles which they are to wrap. During their movement with their needles about the machine, these fingers will occupy about the same position projecting directly downwardly and not being displaced with respect to the axis of the spindle itself. However, at the side of the machine adjacent the mouthpiece and yarn levers these wrapping fingers must be swung bodily inward in order to clear the ends of fingers, especially those fingers which have been raised to a non-feeding position. While it is possible to use a yarn binder and cutter and fingers which would function entirely external to the circle of needles, I do not contemplate such construction but intend to use yarn guiding means of more or less conventional design and to use a yarn binder which will project within the circle of needles, at least to a limited extent. As shown in Fig. 3, the pivoting element 135 has been swung about its pivot 136 to a position wherein the wrap thread guiding fingers are swung inwardly well away from the circle of needles and adjacent the cams 174 which function upon dial needles. In this position there will be no interference and the wrap threads will not become entangled or engaged in any way with the main yarn feeding elements or the binder and cutter. Cams 174 and 175 serve to impart these swinging movements to the fingers. The cam 174 is attached to the underside of plate 9 while the cam 175 is attached in similar manner to the underside of the central hub 113. These cams are so formed with cam edges that a groove of proper contour is left between them within which the pivoting elements 135 may pass. This annular cam groove is concentric except at that side of the machine adjacent the mouthpiece wherein the fingers are to be moved inwardly at a position adjacent the mouthpiece. They will occupy positions as shown in Fig. 19.

Now referring to Fig. 1, the plate 7 intermediate the plates 8 and 9 carries a rotatable assembly which mounts the wrap thread supplies and the take-up devices incidental thereto. A gear 176 fits within an annular space cut within the plate to form a suitable bearing for the gear and this is in turn rotated by a second gear 177 of similar size which is attached to the shaft 46. The gear 177 is pinned by means of a pin 178 to that shaft. This gear likewise fits within a recess cut in the plate and is held in place by a protecting cap or plate 179. A large tube 180 has a lower flange 181 which rests upon gear 176 and

is attached thereto by means of a series of screws 182 passing through a supply supporting plate 183 through the flange 181 and being threaded into the gear. A second circular plate 184 is attached by suitable means to the flange 185 at the top of the tubular element 180. A series of pins 186, Fig. 2, project upwardly from plate 183 and are arranged thereon in staggered relation. There are enough pins so that one supply spool 187 is provided for each finger, that is, in the particular example shown, there would be forty pins and thus forty supplies of wrapping thread.

A series of take-ups are arranged about the outer edge of the plate 184. There is one take-up for each wrap thread or forty take-ups in the particular example herein described. Each of these take-ups comprises a post 188 which carries a slidible collar 189 adjacent its lower end. The yarn as shown at 190 is drawn from a spool or supply, through a wire guide 191 and passes 20 through the post 188 just above the collar 189. A spring 192 is adjustably retained below the said collar and serves to push it upwardly against an adjustable stop 193 whereby the said yarn will be clamped between the elements 189 and 193. Another sleeve or collar 194 is slidable at the upper end of the post and is forced upwardly by means of an adjustable spring tension 195. This collar carries a downwardly projecting finger 196 which, when the collar 194 and finger 30 are urged downwardly against the tension of the spring, will push the lower collar 189 down away from clamping engagement with the yarn whereupon said yarn may be drawn freely from the supply. A take-up arm 197 is pivoted at the top of 35 the post and functions upon an extension of collar 194 to push it downwardly as described. The yarn is threaded through the end of arm 197, then down through an eyelet 198, a second eyelet 199 and through the center of one of the spindles 120, thence to the finger and to the needles. The arms 197 serve to take-up the wrap threads as floats of the same are drawn out and then released, and, as above described, when drawn down to a sufficient extent, will allow thread to be 45 drawn from the supplies.

Those wrap threads which are drawn from the inner circle of supplies first pass through guides 200 and then through one of the guides 191 so that each of the wrap threads will be drawn axially from its supply to avoid any catching or tangling. Due to restricted diameter, the number of eyelets 199 necessarily makes it desirable to stagger them as shown in Fig. 1. It is obvious that with decrease or increase of spindles 120 55 that provision for the supplies may necessitate another arrangement thereof, also different arrangements of the guiding elements and of the take-up devices. These arrangements should be obvious to those skilled in the construction of 60 such machines.

One thing will be obvious from an inspection of Fig. 1, that is, that the entire mechanism may be very easily taken apart if desired. The taper pins which hold the gears to the shafts 43 and 46 as well as those passing through the coupling 47 may be driven out and the cap or cover 40 which is made in two pieces may be removed, whereupon the shaft 46 may be raised and then the gear 41 and short spindle 43 etc. can be removed. Of course, the collars on shaft 46 must be loosened before that shaft can be raised. After removal of the gear 41, spindle 43 and other parts, the shaft 46 may be dropped down through the opening in plate 39 whereupon any of the 75

gears 51, 177 or 103 and other elements may be replaced or removed for any desired purpose.

OPERATION OF WRAP MECHANISM

5 In actual operation of the machine, the shaft 46 is being driven continuously, likewise the entire wrapping mechanism consisting of the gear 102, spindle 120, and the entire mechanism which carries the supplies and take-ups is being driven at the same speed as the needle cylinder itself. During each rotation of the gear 102 the small gears on the spindles 120 are contacted by the teeth on the sectors 141 and 144 so that as the wrap spindle assemblies pass the wrapping point or 10 points, they will be given a turn of 180 degrees by the first three teeth and the remaining 180 degrees at the passage of the second point. These points may be designated as first and second wrapping points and have needles individually 15 selected at each point. The needles that are selectively raised at the first wrapping point will be determined for receiving one of the wrap threads as guided by finger 138, for example, thereafter those needles will be lowered and at 20 the second point, other needles or a different combination of needles will be selectively raised at point number 2. The other finger, for example, finger 139 which would preferably carry a wrap thread of different characteristics or color, would 25 in the second movement of 180 degrees wrap that thread of different characteristics about those needles. This would complete the wrapping and it would then be necessary to rotate each of the wrapping spindle assemblies backwards for 360 30 degrees at some point in their travel about the machine. This is done as above described when the gears contact the sector 144.

The swinging of the fingers inwardly assures that neither the fingers nor the yarns will engage 40 the main yarn guiding elements or the binder and cutter. This swinging movement does not have any effect in the wrapping, and at such times as the spindles are rotated between sectors, the spindles and fingers are axially aligned.

45 Now referring to Figs. 21-28, the first 180 degree movement is shown. The first three teeth of the sector 141 are illustrated in Figs. 21-24; in Fig. 21 the first of these teeth is just being engaged by the teeth 121 of the spindle 120. At 50 that particular time the finger 138 which we will assume to be carrying a black yarn 201 shown as shaded, is in initial position just about to be moved across the leading edge of a group of needles which the said fingers are adapted to wrap in that group. Certain needles shown shaded have been raised to be wrapped at the first stage. For purposes of illustration the wrapping has been going on prior to the showing in these figures and a float of this thread 201 extends from a 55 needle at the opposite end of the group around the back of these needles to the finger. In Figs. 22 and 26, one tooth has been passed and the elements have moved about 60 degrees, the finger 138 thus carrying the thread 201 around the front of needles. In Figs. 23 and 27 the position is shown about 60 degrees further advanced wherein the yarn has been carried around within the hooks of most of the raised or selected needles. In the next pair of Figs. 24 and 28, the complete 180 60 degree movement of the finger 138 has been made and the thread 201 has been placed in the hooks of those needles which were raised at the first wrapping station. Four of such needles were selected, however, in Fig. 28 the first and third needles in that group are not shown as shaded 65

since they have completed or have practically completed their downward movement after being wrapped and preparatory to the selection at the second station. At the particular point reached in Fig. 28, the second wrap thread 202 carried by finger 139 has floated around at the back of the needles in the group and is at substantially the position occupied by the other thread in Fig. 25. At this particular time the wrapping spindle assembly is passing between the groups of teeth 10 on sector 141 and the needles selected at the first station are being moved downwardly while a second selection is being made prior to wrapping at the second point. At this second point other needles shown in Figs. 29-31 as the shaded 15 needles, are raised and the finger 139 will be moved progressively throughout the positions shown in those figures to place the wrap thread 202 within the hooks of such needles as have been raised to receive it. This thread will likewise be 20 passed behind the hooks of those needles which were not raised at the second wrapping point. In Fig. 31 the complete 360 degree movement has been made and the condition therein illustrated will prevail until the teeth on the sector 144 are 25 engaged at which time the wrap thread feeding spindle assembly will be rotated counterclockwise, or in the reverse direction, 360 degrees to bring the elements into the same position they occupy in Fig. 25. This position is shown in Fig. 32 and 30 from a comparison of Figs. 31 and 32 it can be seen that this reverse rotational movement has the effect of untwisting the threads so that the black thread will appear as superposed on the white at the last needle wrapped in the group 35 rather than the white over the black, a condition which prevailed in Fig. 31 or before the reverse rotation took place. The wrapping action is such that the float of one wrap yarn will tie in that of the other.

40 In this example as shown in Figs. 21-32, the panel of needles being wrapped includes six needles, 1, 3, 4 and 6 being wrapped with the thread 201 and needles 2 and 5 being wrapped with the thread 202, these threads being of contrasting colors. The result will be stripes of one color inserted within a pattern of another color. Obviously many changes in the number of needles selected and colors of yarn employed may be 45 resorted to, also the selection of needles may be varied from course to course and the shape or contour of the figure being wrapped may be varied such as making tapering patterns, arrow heads, stems and the like. Any desired disposal of the two wrap threads available may be obtained within possibilities of selection as provided by the needle selecting mechanism later to be 50 described.

55 It is to be noticed that in Figs. 1 and 3 the wrap thread guiding fingers are shown as though they were disposed either parallel or perpendicular to the plane through which the section is taken. This is merely for convenience in the illustration of these parts and in Fig. 19, I have shown the position of these fingers 138 and 139 60 in substantially the relationship which they actually assume at the various points as they progress about the machine. With reference to Figs. 25-31, the wrap thread feeding finger 138 makes a complete wrapping movement of 360 65 degrees about the group of needles which are wrapped thereby. The first 180 degrees of movement of finger 139 does not effect any wrapping of the thread 202, however, the 180 degree movement following is sufficient to introduce that 70 75

thread to the hooks of all of these needles which are to receive it so that prior to the return movement at the opposite side of the machine, Fig. 32, this wrap thread 202 has been taken within the 5 hooks of selected needles and has been supplemented by a main yarn or yarns all of which have been drawn into loops. Obviously, the float of this particular yarn will not pass around back of the needles until the subsequent revolution 10 and subsequent movement similar to that outlined in Figs. 25-31.

NEEDLE AND JACK CAMS

The construction of needles and jacks has 15 been described rather briefly and I will now describe the set-up of butts on these needles and jacks, also the construction and arrangement 20 of cams which are to function on them. As shown in Figs. 52-58, all of the needles are provided with a lower butt 31, these butts being of two different lengths as is the common construction in such machines even though no needle controlling jacks of the type shown are employed. The short butts at the lower ends of 25 needles prevail throughout that sector the needles of which control knitting in the heel and toe of the stocking; the long butts are identified with the instep or front part of the stocking. The division of long and short butts may be in 30 accordance with any arc desired although it is likely that the division will be more or less equal, possibly with a few more needles on the instep side than on the side of the heel and toe. The jacks 29 all have butts 32 which are identical in 35 size and shape. Under each needle and in the same slot therewith the long selecting jacks 37 serve to impart selecting movements for determining the pattern to be wrapped, also at times these jacks serve to control needles for other purposes such as controlling certain of the needles during transfer. Each of these jacks has a plurality of removable saw tooth butts 203, these butts being removable by breaking or in any other desired manner. Each selecting jack also has a saw tooth butt 204 formed more or less as an extension of a square butt 205. Right under this butt 204, alternate 40 selecting jacks are provided with another permanent butt 206, these butts 206 being short butts throughout part of the circle of needles corresponding to the short butt needles themselves while the remainder of the group which do have a butt 206 have that butt of much longer form, all as illustrated in Fig. 57. The purpose 45 for these different lengths will appear as the description progresses. Each of the said jacks 37 has a butt at its lower end as designated at 207. Alternate jacks about the entire circle have short butts 207. These jacks are the ones 50 which have butts 206, but while the butts 206 vary in length at the heel and instep side, all of the butts 207 on those particular jacks which have a butt 206 are of the same length. The remaining selecting jacks have butts 207 of 55 medium or long length. Those jacks at the instep side have long butts at this position while those at the side of the heel and toe have medium length butts.

Now referring to Figs. 33, 34 and the diagrammatic views 44-51, I will describe the cams and briefly state their function. A cam block generally designated at 208 is of somewhat conventional construction and carries knitting cams 209 and 210, center cam 211 center guard cam 212 and a wing cam 213. A plate or cam 214

positioned above the wing cam serves to prevent excessive outward movement of the needle jacks. The cam plate 215 carries a raise cam 216 of somewhat the usual type. The knitting cam 209 has a stem 217 to which is connected a 5 controlling link 218 by means of which it is withdrawn at the desired times by control from a pattern drum (not shown). The center cam 212 is pivoted at point 219 and works adjacent its head and on a pin 220 which engages within 10 a slot in the stem of said cam. The center cam may thus swivel back and forth in the usual way, this cam being shown as moved to the right in all of the diagrammatic figures, but in reverse movements as in the heel or toe, will be swung 15 to the left until one of its top corners engages within the notch 221.

This cam block 208 supports the usual narrowing pick brackets and the narrowing picks 222 and 223 which are of usual construction. The front pick 223 may be withdrawn from action whenever the cam 209 is withdrawn by the usual finger 224 contacting with an extending pin 225 which will rock that pick away from the vicinity of the cylinder. 25

At the opposite side is located the usual widening pick bracket 226 to which are pivoted the widening picks 227 and 228. These widening picks are of more or less standard construction and are controlled in the usual way by a forked element 229 movable up and down as a rod 230 is moved up and down by the usual pick controlling cam elements. Between the widening picks there are located two fixed cams. The upper cam 231 serves to guide needle controlling 30 jack butts down into the picks as shown in Fig. 49 while the lower cam 232 functions with the top cam as a leveling cam for these jack butts and also, during the last stroke is going out of the heel or toe this cam serves as shown in Fig. 51 to bring jacks down to a position where they will be controllable to engage their needles. 35

At either side of the widening pick bracket and of these fixed cams 231 and 232, is located a movable cam 233 at the back of the machine and 40 45 234 at the front. These cams are almost symmetrical in shape with the exception that the cam 234 at the front has its lower point projecting downwardly a little farther than the other cam. These cams serve during the widening as in Fig. 49 to engage the jacks which have been picked down with their needles, and the front cam 234 functions during wrapping to push needle jacks, needles and needle selecting jacks down after the first selection so as to return all of the selecting 50 55 jacks to a non-selected position prior to the passage through a second selecting stage, Fig. 46. Each of these cams is movable by means of connections to a pattern drum (not shown). Cam 233 is slidable in a bracket 235 while the cam 234 60 is slidably retained in a bracket generally indicated at 236.

Another cam 237 is positioned adjacent the cam 233 at the back of the machine and is also slid- 65 able within the said bracket 235. This cam serves to bring the needle controlling jacks which have been raised away from long butt needles during the knitting of the heel and toe back down to engage fixed cam 232 and thereafter the movable cam 234. This cam 237 is likewise movable by 70 means of connecting linkage actuated by means of a pattern drum (not shown).

At the back of the machine adjacent the cam block 208 a pivoting cam 238 is arranged to swing within a bracket 239, this cam being normally 75

- raised to the position shown in Fig. 47 against the tension of spring 240, Fig. 34. When reverse strokes of knitting are taking place as in the heel and toe, the cam 238 will drop down until its lower point rests upon raise cam 216 whereupon needles and needle controlling jacks will be raised to engage knitting cam 210 so as to clear their latches prior to knitting under cam 209 on strokes in a clockwise direction.
- 10 At the front of the machine adjacent the front side of the cam block 208 a bracket 241 carries three cams each movable radially within this bracket by connecting means functioning from pattern control as above indicated. The first of these cams 242, Figs. 34 and 47, for example, serves when pushed inwardly, to raise needle controlling jacks to a position wherein they will be engaged by the wing cam 213 as when going into the heel or toe wherein it is desirable to render the instep needles inactive. The second cam of this group 243 is below and disposed slightly forward of cam 242 and is adapted to engage needle butts 31 to raise them throughout a sufficient distance simultaneously to raise the jack butts 32 so as to engage them with cam 242. The distance that the needles are raised will be such that their butts will pass under cam 242 thereby separating jacks from these needles at that particular point. The cam 243 functions on long needle butts only and thus is movable to a position for engaging those butts but not to a position wherein short butts would be contacted. The third cam in this group indicated at 244 is moved inwardly to engage all needle butts and is moved into position during knitting in circular work but is out during rib and during transfer. It is also in position during the knitting of heels and toes, Fig. 48. This cam merely serves to raise needles to a position wherein their butts will pass beneath the knitting cam 209 but wherein the jack butts 32 will be engaged on top of that cam and will raise needles to a clearing position prior to their knitting under the opposite stitch cam 210. The cam 244 serves practically the same function as the cam 238. The cam 244 is also provided for pivoting as is the cam 238 and a spring (not shown) is used to maintain the point of the cam down against the raise cam. If needle butts pass through in a clockwise direction they will raise this cam 244 if it is in its position against the cylinder, and on the counter-clockwise strokes said butts will ride up the cam as will be described later.
- The cams above described are all located above the usual cam plate 215 and function upon needle butts and on all needle controlling jack butts. A few cams are positioned in brackets beneath the cam plate 215 and function upon butts on needle selecting jacks. Two cams indicated at 245 and 246 are stationary cams which engage the jacks butts 206 for leveling them and for raising those jacks which have butts 206 so as to raise their needles slightly prior to reaching the transfer point on the rotation in which transfer of the dial stitches takes place. This raising of these hitherto inactive needles is for the purpose of bringing their hooks up past the lower edges of dial needles so as to engage the dial loops, all as described in the copending application Ser. No. 86,814. The cam 247 is a sort of raise cam which serves to level up jack butts by engagement of the lowermost butts 207; another fixed cam 248 engages these butts at the upper edges thereof and assists in this leveling operation. Now referring to Fig. 45 a movable cam 249 is attached to engage the

butts 206 and to raise needle selecting jacks whereby needles which were inactive during the knitting of rib work will be raised at the transfer to receive stitches from the dial needles. These butts 206 are peculiar to the needles which are inactive during the knitting of rib and thus it will be only such needles that will be affected by cam 249. During transfer the cam 234 will be withdrawn. A second movable cam 250 is positioned at the base of the cylinder and serves to engage the butts 207 during the knitting of rib so as to raise those cylinder needles which participate in the knitting of rib work for engagement with stitch cam 209 prior to knitting under cam 210. This cam 250, Figs. 44 and 45 will engage only the long and medium butts 207, Fig. 57, during the knitting of rib work, thus the alternate needles having short butts 207 will not be affected. However, during transfer, Fig. 45, this cam 250 is moved in against the cylinder and engages all of these butts 207 since it is desirable at that time to knit on all cylinder needles for a few courses prior to making the actual transfer. This is all described in detail in application No. 144,007, above mentioned. The detailed operation during each phase of knitting will be described later and a full understanding of the working of these cams should be apparent at that time.

YARN FEEDING MECHANISM

Referring to Fig. 38, the yarn feeding mechanism has been illustrated, this mechanism being somewhat simplified over that usually employed. The yarn feeding levers 251 are pivoted at 252 and are urged by springs 253 into a feeding position such as indicated by the lever 251'. Any convenient number of these feeding levers may be employed depending upon the purpose to which the machine is to be put. These levers are held within a mouthpiece generally indicated at 254 which is of sufficient extent to comprise part of a latch ring for controlling latches at positions adjacent the knitting point. There is no latch ring in the usual sense of the term, but needle latches are to be held open by stitches hanging thereon during the part of the rotation in which latches would not be engaged by any positive restraining mechanism. This mouthpiece and the yarn feeding guides 251 etc. are pivoted at 255 on a pin passing through the yarn lever control box 256. This control box has an inclined ledge 257 upon which is secured a sliding block 258 having slots within which a series of plungers 259 are adapted to slide. There is one of these plungers 259 for each of the yarn fingers 251, and, of course, the plungers are in alignment with the fingers and have a rounded end 260 engaging therewith. At a pivot pin 261 passing through the upper part of the lever box 256, I pivot a series of bell crank levers 262, one lever for each of the plungers 259. These levers have knuckles at 263 which engage the plungers. As the levers 262 are moved about their pivot they cause sliding movements of the plungers and whenever a lever is moved in a clockwise direction its plunger is pushed outwardly and upwardly and will incidentally move the yarn feeding levers 251 to a non-feeding position. Upon movements in the reverse direction, the spring 253 will cause those levers to fall to a feeding position. The outer ends of these bell crank levers are twisted into a horizontal plane as shown at 264 and are drilled for the reception of downwardly extending wire rods 265. These rods have collars 266 adjustably attached thereto by

means of suitable set screws or the like, and these collars bear upon the horizontal ends 264 of the levers whereupon downward movements of the wires will pull the levers in a direction to move the yarn feeding means in inoperative position. These wires are controlled from a pattern drum on the main cam shaft of the machine as is the common practice in Banner machines, see U. S. Patent 933,443.

10 LATCH OPENER

During the knitting of rib fabric it is desirable to open the latches of dial needles by positive engagement with a latch opener. This mechanism is illustrated in Figs. 37 and 38. The opener itself includes a slotted block 267 within the slot of which needle hooks are adapted to pass. The front edge of said opener is beveled as illustrated at 268 so that the dial needle hooks will engage that front edge and will be guided upwardly within the horizontal slot. Normally needle hooks would be moving along just a little below said horizontal slot and this lifting movement will cause the hooks to enter therein while, at the same time, it is practically impossible for any 25 of the hooks to engage about the slot. The upper part of the opener above the slot is beveled as shown at 269 and this beveled portion which has a sharp edge is so positioned and is disposed at such an angle that the sharp edge catches 30 under the latches and raises them whereupon they are opened as they progress along the said beveled edge. The latches thus opening are guided by the extending lower surface of the opener as shown at 270 to a position wherein they 35 are safely opened and will remain open throughout the desired period of time. This opener is carried on a T-shaped element 271, this said element being attached by means of screws 272 and 273 to an angular actuating slide 274. The 40 screws 272 and 273 engage within slots in the T-shaped holder and are threaded into one arm of the angular slide. The other arm of this angular sliding element passes through working slots in two lugs 275 and 276 of a bracket 277 45 which is secured to the side of the yarn lever control box. A lever 278 projects upwardly and within a notch at the end of the slot 274 and is pivoted on a tube 279 which passes through this 50 yarn lever control box and to the other end of which is attached a lever 280 which is actuated by link 281 which is in turn connected to certain mechanism functioning from contact with cams on a pattern drum (not shown). This latch 55 opener is timed to be projected inwardly at the start of rib knitting and is withdrawn at transfer.

SPECIAL CONTROL FOR SINKERS

In Fig. 39 the sinker cap is generally indicated at 282 and carries the usual center sinker cam 283 and sinker cams 284 and 285. The said cams are stationary within the cap and function upon sinker butts in the usual way during the knitting of plain fabric. The said cap has a bracket 286 with lugs 287 and 288 within which is adjustably threaded the stop screws 289 and 290 which bump against a bracket 291 which is in turn bolted to the post 157. This sinker cap assembly is oscillated to and fro during reciprocatory work as is the usual practice.

70 During the knitting in rib work it is desirable that the sinkers be projected inwardly so that their nibs will pass beyond the point at which stitches are being drawn over dial needles whereby no detrimental interference may be experienced. A flopper cam 292 is pivoted at 293

and has a point on its sinker butt engaging surface which is adapted to project sinkers inwardly at an early point in the cycle. This flopper cam has a downwardly extending pin 294 which is in turn engaged by a beveled edge on a contact 5 piece 295 carried by bar 296 passing back through individual slots in the lugs 275 and 276. This bar has a notch which is engaged by a lever 297. This lever is fixed to one end of a spindle 298 which passes through the center of the tubular 10 element 279 upon which levers 278 and 280 are fixed. At the front side another lever 299 is fixed to spindle 298 and actuates said spindle, lever and the bar itself by means of a link 300 which is in turn connected for operation by the 15 pattern drum (not shown). The flopper cam has a portion extending to the other side of the pivot 293 designated by numeral 301, and a leaf spring 302 is tensioned to bear against the extension and thus to swing the flopper cam outwardly to the position in Fig. 39 wherein it would not be active. The said cam will be pushed inwardly and will become active during rib knitting as controlled by the bar 296 and other elements functioning thereon, above described. Outward 20 movement of the flopper cam is limited by stop screw 303 threaded into lug 304 bolted to the side of the sinker cap assembly. This flopper cam is brought into play at the beginning of rib knitting and is withdrawn when the dial needles 25 are withdrawn.

During transfer as described in copending application Ser. No. 86,814, the dial is shogged relatively to the cylinder and loops hanging on the dial needles are extended laterally so that 35 the inactive cylinder needles may pass upwardly therethrough. At this particular time sinkers would have been moved inwardly and would be holding the stitches downwardly on the cylinder needles. As the stitches on the dial needles are 40 extended laterally it is desirable to withdraw the sinkers at that particular part of the circle at which transfer is taking place so that the nibs of sinkers may not interfere with the lateral extension of said dial loops. To accomplish this I 45 have provided a cam 305 which engages the sinker butts and is adapted to impart to them a wave outwardly so that sinker nibs will be withdrawn from the vicinity of the dial loops as transfer takes place. This cam 305 is attached to a stem 50 55 306 which slides within a slot cut in the sinker cap and is maintained in place by a plate 307 attached over the slot within which said stem works. The stem has a notch 308 cut in its outer edge within which engages a pin 309 depending from the outer end of one arm of a bell crank lever 310. This lever is pivoted at 311 on the bumper bracket and is controlled by a link 312 pivoted to the other arm thereof. The link 312 is controlled from connections to a pattern 60 drum (not shown).

The notch 308 is of considerable depth so that the pin 309 will not become disengaged therefrom during oscillation of the sinker cap in reciprocating work. The stem 306 has a pin 316 65 threaded therein against which a spring 317 bears and whereby it is held inwardly in an inactive position except when pulled out by means of lever 310, etc.

BRAKE CONTROL

70 A lever 313, Fig. 36, is pivoted on a lug 314 fixed to the base of the machine. This lever 313 functions to control the brake 70, Fig. 5, and is connected thereto by a link 315 passing upwardly at the side of the machine. In application 75

Serial #86,814, previously mentioned, this brake control is thoroughly described so that further description will not be necessary at this point.

SELECTING MECHANISM

Now referring to Figs. 20, 33, 35 and 50, I will describe the mechanism which is employed to control the selection of needle selecting jacks. These jacks as before stated, have a plurality of removable butts 203 and a saw-tooth master butt 204. A series of plungers 318 are slidably mounted within the upstanding posts 319 and 320 which are a part of the base 321 which is in turn bolted to the circular base. The posts 319, 320 have a series of slots formed therein within which the plungers 318 are to slide and wherein said plungers are maintained on an angle as shown in Fig. 33 and 50. Each of the plungers has a butt engaging end which is beveled in a direction to engage the saw-tooth butts on the selecting jacks for raising them in accordance with the angle at which the plunger is disposed. A second set of plungers 322 is similarly held within the posts 323 and 324 projecting upwardly from a base 325. These plunger assemblies are slightly adjustable circumferentially of the base of the machine as well as being adjustable radially thereof.

Each of the plungers 318 has a notch at its outer end within which a knuckle 326 at one end of a lever 327 engages. The levers 327 are to pivot on a post 328 and each lever has a spring 329 attached to the lever and also to a pin or other fixed element on the post 319 or other convenient, adjacent part of the machine. Under the influence of these springs each of the levers will tend to maintain its respective plunger inwardly against the jacks so as to engage butts 203 which pass at the level of that particular plunger. Of course, there is one lever 327 for each plunger.

A series of pattern discs 330 equal in number to the levers 327 are arranged to rotate with a sleeve 331 which is in turn free to be rotated upon a post 332. The post 332 is threaded into a short lever 333 which pivots on the circular base at 334 and which thereby swings about an arc when controlled by a link 335 which pivots at the free end of the lever 333 upon a screw 336. Each of the levers 327 has a toe 337 which is adapted to be engaged by removable butts on the pattern discs 330. For convenience in the illustrations, these discs are shown as having a complete set of butts, however, some of the butts will be broken away so that the toes 337 of the levers would be raised or lowered by butts on the discs and would withdraw plungers 318 or allow them to move inwardly for selecting purposes in accordance with the arrangement of butts on said pattern discs. By means of the link 335 the selecting device may be rendered ineffective at certain times such as in the heel and toe, this being accomplished by swinging the entire pattern disc assembly inwardly until all of the levers were effective to withdraw their plungers.

Of course the pattern discs are continuously rotated, preferably one tooth for each rotation of the machine. A ratchet wheel 338 is also keyed to the sleeve 331 and a pawl 339 engages the teeth on said ratchet wheel to move the pattern disc assembly as desired. The pawl is pivoted at 340 on one end of a swinging lever 341 and is spring pressed into engagement with the teeth of the wheel 338. The lever 341 is fixed to the end of a short shaft 342 which is rotatable

within a bushing 343, Fig. 20. This bushing passes downwardly through the circular base of the machine and a lever 344 is fixed to the lower projecting end of the shaft 342. On each rotation of the machine this lever 342 is contacted by a cam 345 which is connected for rotation upon the ring gear 3, said cam being attached to an angular bracket 346 which is in turn bolted to depend from the underside of said gear. The lever is moved in one direction by means of a spring 347, Fig. 35 while ratcheting movements are imparted as the cam 345 contacts lever 344 and thus moves the pawl 339 a distance of one tooth against the resistance of spring 347.

The link 335 is connected to suitable pattern mechanism and during the knitting of the heel and toe and at other times when it is not desired to form a pattern, the pattern disc assembly is swung to a position so that all plungers 318 will be withdrawn. The said plungers raise jacks having butts at the level of selecting plungers. Such movement imparted by the plungers is merely one of preliminary selection only. A cam 348 is arranged to engage the master butts 204 after the selecting jacks have been elevated by one of the plungers. This cam 348 is mounted on a stem 349 which is in turn to be pivoted within a support 350 attached adjacent the post 320 as shown in Fig. 35. This cam 348, the plungers 318 and supporting means therefore are very similar to those shown in U. S. Patent 2,067,877. The cam 348 is held inwardly in active position by means of a spring (not shown) and upon improper contact of butts 304 therewith, will be swung out to avoid danger.

At the second selecting stage plungers 322 are accompanied by a second cam 348' and the remaining parts therein shown are practically identical with similar parts just described at the first selecting point. For convenience some of these parts are merely numbered with the same numerals having primes and no detailed description will be given here.

The cam 345 is to be pivoted at 351 on the said bracket 346 and is stopped from swinging in one direction beyond the position shown in said Fig. 35. However, that cam is retained in the position shown by a spring 352, and in the heel and toe during reciprocation, the cam can swing against the tension of the spring and will have no effect on levers 344 and 344' in clockwise movements.

For the purpose of making a plain sole, or at any other time, blotting out or cancelling selections made by the plungers 318 and 322 on a part or all of the selecting jacks, cams 353 and 354 are formed on the ends of stems 355 and 356. These stems slide in horizontal slots at the very top of the post 319, etc., and serve to project the said cams in to engage above the square butts 205 on top of the master saw tooth butt 204. These square butts 205 may be formed on some of the selecting jacks to the exclusion of others. The square portion may be made removable if desired. When moved inwardly, said cams will immediately lower such selecting jacks as have been raised by the plungers. This lowering of jacks serving to cancel what selection has been made since the saw tooth or master butts 204 will pass under cams 348 or 348' and the selection will never be completed. For instance, if the butts 205 are formed on jacks at the side opposite the instep, the selection which was imparted throughout the entire knitting of the leg of a stocking may be so modified by these cams 353 and 354 as to discontinue the pattern throughout.

the sole of the foot but to continue it throughout the instep or at needles the jacks of which do not have the butts 205. The entire pattern might be discontinued by pushing in both cams 353 and 354 if butts 205 were present on all of the selecting jacks. Of course, a more satisfactory way to do that sort of thing would be to control the selecting means by the links 335 and 335' so as to make no selection at all. In other instances it may be desirable to retain the butts 205 on the needles and to employ either one of the cams 353 or 354 separately to alter the pattern by discontinuing wrapping at one point or the other, that is, to discontinue the wrapping by one of the fingers 138 or 139. Still another possibility is that of retaining the butts 205 on the instep side so that a plain foot can be formed by employing both of the cams 353 and 354 to discontinue patterning in the instep while the sectors 141 and 144 may be raised to discontinue wrapping in the sole. It is obvious that either the sectors or the cams 353 and 354 may be used to knit a plain sole.

One particular set-up of butts has been shown in Fig. 57, this figure illustrating a few jacks in the instep or long butt side and a few in the sole or short butt side. The selecting butts 203 are arranged in one typical pattern while the butts 205 have been broken away in the instep portion so that the cams 353 and 354 may be used to knit a plain sole.

The cams 353 and 354 are to be controlled by connecting linkage to the pattern drum of the machine, such control being well known and not being necessary of illustration in this case.

35 OPERATION

Rib top

Now referring to the diagrammatic Figs. 44-51 and 52-58, I will describe the operation of the 40 machine throughout the characteristic steps of knitting a stocking.

The stocking is started by knitting a rib top on all the dial needles and on the intervening or every other cylinder needle. During the knitting of this rib top the dial needles are controlled by the usual dial needle cams for causing them to pass through a stitch drawing wave, while the cylinder needles are controlled at the main cam block, but are in effect, selected by the needle 45 selecting jacks to knit at that point. In Fig. 44 the cam 250 is in position to engage the long and medium butts 207, but not the short butts at that elevation. The jacks are leveled by means of cams 247 and 248 after which have passed through the cams 245 and 246. The movement 50 through these first cams 245 and 246 is more or less an idle movement and merely raises those cylinder needles which are not participating in the rib knitting. They are immediately moved down by the cam 234 after they pass under cam 55 232. The cams 232 and 234 contact the needle controlling jack butts only. When the butts 207 are contacted by cam 250 the needles controlled by these alternate jacks will be raised so that 60 their butts will pass along the pathway 357 while the jack butts 32 will be moved up to the pathway 358. The needle and jack butts on those intervening needles which do not knit in the rib work will move along at a lower level and will finally 65 pass through under the cam block in pathways 359 and 360. These butts will straddle the cam 211. The needles which do knit will be drawn up to a clearing position as the jack butts ride up the top side of cam 209 and will thereafter 70 be pushed down by cam 212 to engage the knit-

ting cam 210 and to knit under that cam. After knitting, both groups of needles and their jacks pass in the same pathway being guided over the raise cam 216. The butts 207 of the jacks controlled by cam 250 move through pathway 361 5 while the short butts on the intervening jacks pass along at a lower level 362.

At the start of knitting this rib top dial needles are held for a few courses to knit a short welt according to the usual custom. At the end of 10 knitting this welt the last course may be knitted loosely so as to provide longer stitches for the transfer. At the end of rib knitting and just prior to transfer, two or more courses are knitted on all cylinder needles to provide what I term 15 as fill-in courses, these being described in co-pending application 86,814 and not being an essential part of this case. In order to knit these courses prior to transfer the cam 249 may be moved into place so as to act in conjunction with 20 the cam 250 and thus raise all of the cylinder needles for knitting. During this knitting of two or more courses the cylinder needles are withdrawn and merely hold their stitches.

Transfer

25

Now referring to Fig. 45, the mechanism is shown in position for transfer of the dial stitches to the intervening cylinder needles which did not knit during the knitting of rib work. At this 30 time cam 234 is withdrawn and cam 249 is inserted if it was not previously inserted for the knitting of the fill-in courses. In regard to this last feature, the fill-in courses might have been knitted by another means, for instance the cam 35 244 might have been inserted at that particular time in lieu of cam 249.

The cam 249 will raise those needle selecting jacks having butts 206 and thus the needles and needle controlling jacks which are to take the dial 40 stitches. The dial has in the meantime been shogged and the stitches held on dial needles will have been extended laterally so that they may be penetrated by the said cylinder needles. The cam 246 raises jacks and incidentally cylinder needles to take the stitches, up to an overlapping position with respect to dial needles. All this is described in detail in application 86,814 above mentioned. Those jacks will be raised in the pathway 363 and the corresponding needle 50 butts will be raised into pathway 364 while the jack butts move in pathway 365. It will be noted that these pathways 364 and 365 are at the same elevation as the pathways 357 and 358, Fig. 44, that is, a pathway in which the said needles will be caused to knit through the cams 208, 210, etc. The cam 250 is preferably left in position so that the other needles will be raised to the pathways just mentioned and thus all needles will be knitting on the same rotation just after transfer, that 55 is, it is not necessary to make an idle rotation before resuming the knitting after the loops have been dropped from the dial needles and taken by the cylinder needles. After transfer the dial needles are withdrawn into the dial and then 60 serve no further function throughout the knitting of the rest of that particular stocking. At the transfer the sinker cam 305 is pulled outwardly as previously described and moves sinkers to a position wherein they do not interfere with the 65 lateral extension of the dial loops.

Leg and/or foot and wrap stripe knitting

Now referring to Fig. 46 I have shown knitting during circular work wherein needles are being 75

selected for wrapping, this selection taking place at two selecting stages as for the wrapping of "color side of color" and "color within color" patterns. The needle butts and needle controlling jack butts are passing in the usual pathways under cams 233 and 232; the jacks are likewise moving through cams 245, 246, 247 and 248. The first group of plungers 318 will be encountered by the jacks whereupon some of them will 10 be selected as plungers which are moved inwardly engage butts passing in alignment therewith. These jacks will be moved upwardly so that their butts 204 will be raised to the pathway 366. Thereupon those jacks will be raised as 15 the butts 204 ride up the cam 348. The corresponding needles and their controlling jacks will be elevated as indicated by pathways 367 and 368. At that topmost position needle hooks will be elevated above the dial and to a position to be 20 wrapped by the fingers 138. At that time said fingers make a movement of 180 degrees as previously described.

Said selected needles remain at the wrapping elevation just long enough for the wrap thread 25 to be taken within the hooks thereof whereupon cam 234, now moved inwardly against the cylinder, will engage the needle controlling jack butts 32 and will return the needle, needle controlling jacks and needle selecting jacks to the level 30 which they occupied prior to the first stage of selection.

Just after passing the cam 234 the needle selecting jacks are again presented for selection by a group of selecting plungers 322. Certain of 35 the plungers may be selected and raised so that their master butts engage cam 348' whereupon they will be elevated to the pathway 369 and the corresponding needle and needle controlling jack pathways will be indicated at 370 and 371. The 40 second wrapping by finger 139 takes place at this point and such needles as were raised will have a thread which will probably be of a different color placed in the hooks thereof at this station. The needles then pass through the cams 209, 210, 45 etc., and knit as before described. Needle selecting jacks will be lowered to the lower pathway 372 as the needles knit.

It is obvious that for some simple wrap patterns it would not be essential to use both of the 50 selecting stations, neither would it be necessary to employ the cam 234 for returning the elements to non-selected position if only the first stage of selection were to be employed. During the knitting of the leg it is probably desirable to 55 form some sort of a pattern about the entire circumference or a portion of the stocking. During the knitting of the foot it is quite common to wrap in the instep only and to knit a plain sole, possibly a reinforced sole. The selection may continue as in the leg after the 60 instep is reached and the plain sole may be knitted merely by discontinuing the rotation of those wrap spindle assemblies which are located at that section of the stocking. The sectors 141 and 144 will be raised by the mechanism previously described and will function only on the gears having long teeth so that no wrapping movement will be imparted to the fingers at the opposite side and thus it will not make any difference whether needles are selected at that side 65 or not. The cams 353 and 354, Fig. 50, may be employed to effect the knitting of a plain sole and in that event it may not be necessary to raise the sectors 141 and 144. The cams 353 and 354 will merely cancel whatever selections 70

have been made at the side of the stocking which is to be knitted plain, the jacks at that side having the butts 205 retained thereon while such butts are not in evidence at the opposite side. Other combinations and other uses for the cams 353 and 354 as well as the pattern control and raising of the selectors 141 and 142 will be evident to the skilled knitter. It is not the purpose of this description to go into more detail than is necessary to describe the knitting of a common 10 type of hosiery.

Going into heel and toe

Now referring to Fig. 47, I will describe the manipulation of cams and the manner in which 15 the needles and needle controlling jacks are caused to operate. The needle selecting jacks are not used at this particular time. In the event the leg was being patterned by wrapping, the selecting drums or discs will be moved to 20 such a position that the selecting plungers will all be withdrawn as previously described. The needle butts pass along the raise cam 216 in the usual way and the selecting jack butts pass under cams 233, 232 and under 234. The instep 25 cams 242 and 243 are moved into active position; the cam 242 moves clear in against the cylinder while the cam 243 moves in to a position for engaging long butts 31 but not short butts. The cam 244 will still remain in the position it occupied 30 during the knitting of the leg. The long needle butts pass up cam 243 and thus raise the needle controlling jack butts 32 in the pathway 373 so that they contact and ride up cam 242 passing along to engage the wing cam 213 and to 35 be raised over that cam. This separates the long butt needles from their jacks. The long needle butts pass under cam 242, over cam 244 and then under the stitch cam 209. They move around in pathway 374 thus moving through the 40 cam block without knitting thereat. Once the jacks 29 have been disconnected from the long butt needles by means of the instep cams, those cams may be withdrawn and of course, the said disconnected jacks will merely move back and 45 forth in a pathway 375 above cam 213 and beneath the cam 214. The short butt needles will not be affected by cam 243 so that they will move along in the pathway 376 and will then move up the cam 244 so that their jacks engage above 50 stitch cam 209 and thereafter said needles will knit at the stitch cam 210 in the usual way. The cam 238 swings upwardly as needle butts pass under it in this direction. The description just given is a description of the operation during 55 the last course in the leg prior to starting reciprocations in the heel, or similarly, the last course in the foot prior to starting the toe.

Heel and toe, narrowing and widening

In Fig. 48 I have illustrated the picking of jacks so as to narrow the heel or toe pocket. The narrowing is shown in a counterclockwise direction although similar procedure would be evident at the stroke in the opposite direction. The narrowing picks 222 and 223 are in position rested on the top of cams 209 and 210 so as to engage the first butt on the needle controlling jacks functioning with short butt needles. The pick 223 has just engaged the leading one of these butts 70 32 and has picked it from the pathway 377 to the elevation shown wherein it will contact the wing cam 213 and will then avoid the end of the group of jack butts moving in pathway 375. The pick will then fall and rest on the passing 75

jack butts 32. This picking will alternately withdraw one jack at either end of the group and incidentally its needle from the group knitting the heel or toe in each reciprocation. The result 5 will be knitting of the heel and toe of conventional type, although the picking is done on the jacks and the needles remain in a low elevation wherein they have their latches held open by means of the last drawn stitches. Cams 238 and 10 244 will be swung upwardly on alternate strokes and will also serve the usual purpose of raising the short butt needles so that the jacks move up the pathway 377. The needles which still have 15 controlling jacks associated therewith will pass 15 in the usual pathways through the cam block and will knit alternately under the cams 209 and 210.

In Fig. 49 I have shown the operation of the widening picks 227 and 228 as they function to move jacks downwardly so that they may be 20 engaged with their respective needles. During the narrowing the raised jack butts 32 continuously pass under cam 231 which is always maintained in stationary position. That cam 231 causes a depression of the jacks from the pathway 25 375 but is not sufficient to prevent their striking the wing cam 213 and being guided over that cam again. As soon as the widening picks are brought into play, the group of raised jack butts will pass under the cam 231 and the leading butts, two in number, will be engaged by the pick 227, Fig. 49, and will be brought down to a pathway 378 so that cam 233 will then move them downwardly until they engage the lock with their 30 respective needles. This means that these needles will then resume knitting in the heel rather than passing idly through the cam block. According to the usual practice, the narrowing picks still continue to function so that this double picking in a downward direction is in effect no more than a returning to action of a single needle on 35 each stroke. On the reverse stroke the pick 228 will function in similar manner and cam 234 will lock the jacks which are picked downwardly into engagement with their needles as above described.

45 Going out of heel and toe

Referring to Fig. 51, I will describe the manipulation of cams and other instrumentalities upon going out of the heel and/or toe whereupon knitting is to be resumed in straight-a-way. The 50 heel or toe having been completed so that a complete pocket has been knitted wherein all needles that were withdrawn during narrowing have been returned during widening, the needle controlling jacks individual to the long butt needles are to 55 be brought back into locking engagement with those needles, to effect this, cam 237 is moved in against the cylinder and the jack butts 32 will be engaged thereby and moved downwardly to a pathway 379. These jacks are further lowered 60 by means of cam 232 and will be locked with their needles by the movable cam 234 which is in position at this particular time. This all takes place in the first complete rotary course after the heel and toe and the needles will all knit passing 65 through the cams at the main cam set on this stroke. The cam 244 will remain in position as usual during rotary knitting. The selecting mechanism will be returned to operation at this time if the stocking is to be ornamented by a 70 wrap pattern. If the foot is to be knitted at this time, a plain sole may be made in accordance with one of the schemes indicated above. Once all the jacks have been returned to active engagement with their needles, the cam 237 is 75 withdrawn.

Conclusion

I have described one particular embodiment of the invention concerned and that description and illustration is to be taken as illustrative in one manner of practicing said invention and is not to be interpreted in a limiting sense. There may be many changes all falling within the scope of the invention which will be obvious to those skilled in the art and all such changes are intended to be included within the scope thereof. The invention is to be limited only as defined in the claims.

I claim:

1. In a knitting machine, the combination of 15 a cylinder and dial, needles in said cylinder and dial, said cylinder having twice as many needles as the dial, means for imparting stitch drawing movements to the needles whereupon rib fabric may be knitted at times and at other times, certain cylinder needles only may be controlled for 20 knitting plain fabric, means for transferring stitches from the dial needles to certain of the cylinder needles and means for wrapping pattern threads about selected needles including wrap 25 thread guiding devices, said devices being constructed to wrap threads of one characteristic about needles at one wrapping point and threads of another characteristic about the same group of needles at a second wrapping point, and selecting means for said needles adapted to select 30 them at the first wrapping point, to return them to non-selected position after being wrapped at the first point, and then for imparting a separate and distinct selecting movement to any of 35 the needles desired at a second wrapping point whereupon said needles may have a thread of either characteristic wrapped thereabout as desired.

2. In a knitting machine, the combination of 40 a cylinder and a dial, needles in said cylinder and dial adapted to knit rib fabric at times, plain fabric at other times and to transfer stitches from said dial needles to certain of the cylinder needles when knitting plain fabric in continuation of the rib fabric, means for selecting cylinder needles 45 at two points in their travel about the said machine and for returning those needles selected at the first point to non-selected position prior to their being engaged for selection at the second point, wrapping means functioning at the 50 first point to place a wrap thread of one characteristic in the hooks of selected needles, said wrapping means functioning by further movement thereof to place a wrapping thread of another characteristic in the hooks of selected needles at 55 the second wrapping point.

3. In a knitting machine, the combination of 60 a dial and cylinder, needles in said dial and cylinder and cam means for imparting stitch drawing movements to said needles for knitting rib fabric at times, and at other times, for knitting plain fabric on said cylinder needles only, means whereby stitches are to be transferred from said dial needles to certain of the cylinder needles, means for selecting any desired needles in a group of needles at a first 65 selecting station and means for selecting any desired needles in that same group of needles at a second selecting station, means for returning those needles which were selected at the first 70 station to a non-selected position before they are to be engaged for selection at the second station, and means for wrapping needles selected at the first station with a thread of one characteristic and means acting in conjunction with said first 75

wrapping means to wrap a second thread about the needles of said group which are selected at the second wrapping station.

4. In a knitting machine, the combination of 5 needles, needle controlling jacks and needle selecting jacks, said needles having butts thereon by means of which they are controlled for certain movements and said needle controlling jack having butts thereon and being engageable and dis- 10 engagable from said needles whereby movements of the said jacks are imparted to the needles and at other times, said needles and jacks may move independently, means for imparting selections to the needles through said selecting jacks and 15 wrapping means constructed to wrap pattern threads about such needles as are selected to receive said threads.

5. In a knitting machine, the combination of 20 needles, needle controlling jacks and needle selecting jacks, certain needles and needle controlling jacks having cooperating means whereby movements of the jacks are imparted to the needles at times, while at other times needles and needle controlling jacks are to be moved in- 25 dependently, means for imparting selecting movements to the needles through said selecting jacks, and thread wrapping means for wrapping pattern threads about such needles as are selected.

6. In a knitting machine the combination of a 30 cylinder and dial, needles, needle controlling jacks and needle selecting jacks in the cylinder, and needles in the dial, means whereby said cylinder needles and needle controlling jacks are moved while connected for drawing stitches and 35 at other times, are to be moved independently, means whereby the dial needles function with certain of the cylinder needles to knit rib fabric and other means for imparting movements to 40 said cylinder and dial needles whereby loops are to be transferred from the dial needles to cylinder needles, selecting means for imparting selecting movements to the selecting jacks and thus to the needles, wrapping means functioning to impart 45 wrapping movements to pattern threads for placing those threads in the hooks of selected needles.

7. In a knitting machine, the combination of a cylinder and dial, needles, needle controlling jacks and needle selecting jacks in the cylinder, 50 and needles in the dial, means whereby said cylinder needles and needle controlling jacks are moved while connected for drawing stitches, and, at other times, are to be moved independently, means whereby said dial needles function with 55 certain of the cylinder needles to knit rib fabric and other means for imparting movements to said cylinder and dial needles whereby loops are to be transferred from the dial needles to cylinder needles, selecting means for imparting move- 60 ments to the selecting jacks at a first point for raising certain of the needles at that point, means for returning said selected needles to a non-selected position, other selecting means for selecting needles at a second point, and means 65 carrying two wrap threads and functioning to wrap one of the threads about the needles selected at the first point and the other thread about such needles as are raised at the second point.

8. In a knitting machine the combination of a 70 cylinder and a dial, needles in said cylinder and in said dial and needle controlling jacks associated with said needles in the cylinder, cams for imparting movements to said cylinder needles and said needle controlling jacks, the relation-

ship being such that needles and jacks move as a unit at certain times and at other times, they move individually, means for controlling the dial needles to knit in conjunction with cylinder needles to knit rib fabric and other means for causing the dial stitches to be transferred to cylinder needles, means for selecting needles in a group of needles for raising them to receive wrap threads at one point, means for returning said selected needles to a non-selected position and 10 second selecting means for raising other needles in the same group for receiving a wrapping thread at a second point and wrapping means carrying two wrapping threads and functioning to wrap one of the threads about those needles selected at the first point and thereafter to wrap the second thread about needles which are selected at the second wrapping point.

9. In a knitting machine, the combination of a 20 series of needles, means for selecting predetermined ones of said needles for raising them to be wrapped at one point and other means for raising needles to be wrapped at a second point, wrap thread carrying means individual to a group of said needles and carrying two threads, means 25 for moving said wrap thread carrying means so that one of the said threads will be wrapped about raised needles in said group at the first point and so that the second of said threads will be wrapped about those needles which have been 30 selected and raised at the second point.

10. In a knitting machine the combination of a cylinder, needles independently movable within said cylinder, means for selecting certain needles to raise selected needles in a group at 35 one point and other selected needles in said group at a second point, wrapping means including a spindle and opening yarn carrying fingers associated with said group of needles and means for swinging one of said fingers about selected 40 needles in said group to place a wrap thread in their hooks at the first selecting point and for imparting a further rotative movement at the second point so as to wrap those needles in the group which are selected at the second point 45 with a thread of different characteristics from that wrapped at the first point.

11. Wrapping means for knitting machines of the type described including rotating spindles, a plurality of fingers depending from said spindles and for guiding wrap threads to the needles, means for rotating a spindle for placing one wrap thread in the hooks of needles and means for thereafter imparting a further rotation so as to place a second thread in the hooks of 55 needles at a different time from that at which the first thread was passed about its needles.

12. Wrapping means for knitting machines of the type described including a rotating spindle, a plurality of fingers depending from said spindle 60 and rotatable therewith, said fingers being positioned to circumscribe a group of needles when said spindle is rotated and means for rotating said spindle to move one of the fingers around the group of needles for placing a wrap thread 65 in the hooks thereof at one time and thereafter, for imparting further rotation to pass another of said fingers about said group of needles.

13. Wrapping means for knitting machines of the type described including a rotating spindle, a 70 plurality of depending fingers associated with said spindle and adapted to guide wrap threads to a group of needles associated with said spindle, means for imparting separate partial rotations to said spindle to pass first one finger and then an-

other about said group of needles for wrapping the threads about them and other means for thereafter rotating said spindle reversely to its initial position.

14. Wrapping mechanism for knitting machines of the type described including a rotating spindle, a plurality of depending fingers for guiding wrapping threads to a group of needles associated with said spindle, a gear on said spindle, a sector for engaging said gear and rotating the spindle, and another sector for imparting reverse rotation to said spindle to return it to its initial position.

15. Wrapping means for knitting machines of the type described including in combination a wrapping spindle carrying a plurality of depending fingers, means for moving said spindle bodily in timed relation to movements of a group of needles, a gear on said spindle, a sector for imparting needle wrapping movements to the fingers so as to move them about said group of needles in two individual steps, and means for rotating said spindle reversely to return it to its initial position.

16. Wrapping means for knitting machines of the type described including in combination a plurality of spindles carrying depending fingers, each spindle and its fingers being adapted to wrap pattern threads about a group of needles associated therewith, means for rotating said needles bodily about the machine and other means for

rotating said spindle bodily in timed relation so that each spindle and fingers remain in position adjacent its group of needles, a gear on each

spindle, a sector for engaging said gear and for imparting movements to said gear so as to rotate the spindle and fingers in two separate and individual movements, and means for thereafter returning said spindle and fingers to their initial

position.

17. Wrapping means for a knitting machine including a rotating spindle, depending fingers for guiding wrapping threads to a group of needles individual to said spindle and fingers, a gear on said spindle, a sector for imparting movements to said gear, said sector having spaced groups of teeth whereby said spindle is rotated throughout a predetermined arc at two spaced positions in its travel past said sector.

18. Wrapping means for a knitting machine including a spindle, depending fingers on said spindle, a gear on said spindle and a sector for imparting rotating movements to said spindle as it is moved bodily past said sector, and means for maintaining said spindle in fixed position when the gear is not engaged by said spindle.

19. Wrapping means for a knitting machine including a spindle, depending fingers for guiding wrap threads pivoted to said spindle, and cam means functioning to maintain said pivoted fingers in position for wrapping threads carried by the fingers about needles to be wrapped, and other cam means for bodily swinging said fingers

away from needles at certain points in their travel about the knitting machine.

20. Wrapping means for a knitting machine including a plurality of spindles, fingers depending from said spindles and pivoted to swing relatively thereto, means for bodily rotating said spindle and fingers in unison with a series of needles about said machine, and cam means for maintaining said fingers in wrapping relationship to said needles at a part of their travel about the machine but for swinging them away from said needles at other parts of the said travel.

21. Wrapping means for a knitting machine including in combination a plurality of spindles, depending fingers pivoted beneath said spindles and adapted to guide wrap threads to needles to be wrapped, gears on said spindles, sectors for rotating said spindles to impart wrapping movements to fingers and another sector for reversely rotating said spindles to initial position, and a cam for maintaining said pivoted fingers in alignment with said spindle whereby needles may be wrapped as the said spindles and fingers are rotated by the sector but for swinging said fingers bodily away from needles at other positions in their travel about the machine.

22. In a knitting machine, wrapping means for a series of independently movable needles including a plurality of spindles, wrapping fingers depending from said spindles, means for moving said spindles bodily relatively about said machine, gears on said spindles, a sector for engagement with said gears to rotate them and the

fingers for wrapping groups of needles, another sector for reversely rotating the spindles to initial position, said gears having teeth of different lengths and said sector being movable

along the length of said gears whereby rotative movements may be imparted to some of said spindles but discontinued with respect to others.

23. In a knitting machine, wrapping means for wrapping pattern threads about selected needles including a plurality of spindles, depending fingers for guiding wrap threads to the

needles, a gear on each spindle, means for bodily moving said needles, fingers, and gears so as to maintain them in association with a group of needles adapted to be wrapped by each of the

fingers, sectors for engagement with said gears, one arranged externally and the other internally

thereof, whereupon movements are imparted in one direction for wrapping and in the other direction to return the spindle, fingers and gears to initial position, said sectors being vertically

movable and said gears having teeth of different lengths whereby said gears may be caused to be rotated continuously as said spindles and gears sweep past the sectors but whereby certain of

the said gears and spindles may be held stationary as the sectors are moved out of engagement with those having shorter teeth.

ROBERT H. LAWSON.
